(57) **CLAIM**

The ornamental design for a vehicular exterior trim, as shown and described.

DESCRIPTION

The FIGURE is a front view of a vehicular exterior trim, of the new design.

The broken and dotted line rectangle shows a portion of the exterior trim, outside of which forms no part of the claimed design. The portions of the vehicle shown in broken and dashed lines throughout the drawing are for illustrative and environmental purposes only, and form no part of the claimed design.
